METHOD OF AND MEANS FOR LAYING OUT
MODEL RAILROAD TRACK

William H. Himes, Dayton, Ohio

Application May 2, 1955, Serial No. 505,297

15 Claims. (Cl. 1—60)

This invention relates to a method of and means for defining and forming curves in model railroad track in preparation for spiking to a road bed.

For use in model railroading there has been made commercially available a track made in appropriate scale proportions and usually sold in three-foot lengths, the track being flexible so that it may be installed on the road bed according to any desired curvature and then piked to the road bed to maintain such curvature. At present, to construct a curve it is customary to strike the desired radius with suitable compass-like tools and then to calculate and lay out the proper easement or transition curve leading from the straight section of track into the portion of principal curvature and out of such portion into another straight section of track. The transition curve may also be established by means of an involute involving the use of several diminishing radii greater than the desired radius. Whatever method may be used, the layout of the transition curve starts at a point contiguous and at right angles to the straight track and ends at a similar point with respect to the adjacent end of the desired radius or principal curve. These points are sometimes called tangent points and will hereinafter be so identified. After the desired radii have been struck and an appropriate layout made, a flexible track section is hand formed to a matching curvature and as so formed is fastened, as by "spikes" to the underlying support. The described method of establishing and forming track curves thus suffers from certain disadvantages. The layout of the proper curve and its easement is a relatively time consuming operation and a not inconsiderable amount of skill is required for its proper execution. Also, the hand forming of a track section does not readily result in the forming of a smooth curve and care must be exercised to avoid kinks and undulations.

An object of the instant invention is to simplify the establishing and forming of curves in model railroad track and to insure smoothness and accuracy in the configuration of such curves.

Another object of the invention is to obviate the need for executing a preliminary layout of the principal curve and its easement.

A further object of the invention is to present a generally new method of laying model railroad track, involving the use of templates serving to form the track to the desired radii as well as to hold the track so formed while it is being spiked to the road bed.

Still another object of the invention is to provide template means useful in the constructing of curves in model railroad track.

Other objects and structural details of the invention will appear from the following description when read in connection with the accompanying drawings, wherein:

Fig. 1 is a top plan view of a template of standard radius and a transition template in end to end position as used in the forming of a curve, there being shown in conjunction with the templates radius and angle lines

useful to an understanding of the construction and mode of use of the templates;

Fig. 2 is a view in cross section of a section of track of the kind curved in accordance with the teachings of 5 the instant invention;

Fig. 3 is a top plan view of a portion of the track shown in Fig. 2;

Fig. 4 is a view similar to Fig. 3, with the rails removed and showing only the tie strip;

10 Fig. 5 is a view similar to Fig. 2, showing a template in place in the track and further showing the track spiked to a road bed;

Fig. 6 is a view similar to Fig. 1, showing a plurality of templates of a series of standard radii, including transition templates, and showing radial lines extending therefrom;

Fig. 7 is a view similar to Fig. 6, showing the series of 15 templates of standard radius arranged for use without the transition templates;

20 Fig. 8 shows how a transition template may be used to obtain a reverse curve;

Fig. 9 is a detail view in plan of a template of standard 25 radius showing the scale marking thereon useful in forming curves connecting straight away portions of other than 90° relationship;

Fig. 10 is a view showing how a transition template is 30 installed in the track;

Fig. 11 is a view like Fig. 10, showing the track bent to and conforming to the curvature of the transition template;

35 Fig. 12 is a view similar to Fig. 11, showing the template of standard radius installed in the track beyond the transition template;

Figs. 13 and 14 are views of a curving track, showing 40 successive steps in the forming of a 30°, 45°, 60° curve and the like.

Referring to the drawings, a model railroad track of the kind with which the instant invention is concerned comprises a fiber tie strip 20 presenting simulated ties 21 45 interconnected by integral laterally spaced apart ribbons 22 and 23, the latter being separated between alternate ties by cuts 24 and 25. The arrangement is such as to provide for twisting or bending of the tie strip 20 in its own plane about its longitudinal axis. Mounted on the strip 20 in overlying superposed relation to the ribbons 22 and 23 are brass rails 26 and 27, the rails being secured to the tie strip by clips 28 installed in openings 29 in the strip 20 and being U-shaped for clamping engagement with the flange of a rail and the underside of the tie strip. The track assembly as described is in 50 use usually secured, as by spikes 31 to a wood road bed 30. A template 32 is shown in Fig. 5 received between the rails 26 and 27. The template 32 is made of a relatively heavy and rigid material such as steel, and, as will be understood, when curved may be used to enforce a corresponding curvature of the track, which is bent by hand to conform to the shape of the template. The brass rails 27 and 26 are flexible for this purpose and the tie strip 20, as above mentioned, has a freedom of 55 flexure defined by the cuts 24 and 25. As will be further understood, a template 32 may be used to establish a curvature for the track and will also serve to hold the track in the accomplished curve while the spikes 31 are being driven permanently to lay the track in its curved formation to the road bed 30. The template has a thickness approximately twice the height of the rail and a width calculated to permit of its installation between the rails with a slight press fit. It will be understood, in this latter connection, that the template is designed for use with track of a certain gauge, for example HO gauge.

60 As shown in Fig. 1, the template 32 is curved in accordance with what may be termed a desired or standard

radius and is of a length and curvature to define a principal curve, as distinguished from an easement or transition curve. The latter, in accordance with the instant invention, is achieved through use of a second template 33. The term "Standard radius" as used herein is derived from standards established by model railroading associations by which it is sought to make track layouts uniform in elements of basic design for simplified supply by manufacturers of track and car parts and accessories. Thus, in the HO gauge track above mentioned, wooden road bed 30 is supplied in arcuate lengths which progress in radius by increments of two inches. That is, a curved road bed of 18" radius is available, as is one of 20", 22" and so on. It is intended, in accordance with the instant invention, to provide a template 32 for each of these so-called standard radii. As indicated in Fig. 1, lines 34 and 35 tangent to the ends of the template 32, converge at a point 36, as does any line, for example, a line 37, drawn radially from the template any place between the ends thereof. Point 36 is thus the center of the arc defined by the template and the line 37 defines the individual standard radius dimension thereof. The transition template 33 conforms to a radius which is a predetermined multiple of the standard radius, in the illustrated instance three times the standard radius. In use, the transition template 33 is placed in end to end relation to the template 32, with the adjacent ends of the template in substantially abutting relation as shown in Fig. 1. So positioned, lines tangent to the end of the template 33 converge at a center point 38, a line 39 at one end of the template coinciding with the line 35 and passing through the center 36 of the standard radius template 32. The other line 41 is substantially tangent also to the end of the straight away portion of the track, here indicated diagrammatically at 42. A radial line 43 represents the transition template radius.

The standard radius template 32 may be considered to lie within and be embraced by a right angle defined by a vertical line 44 and a horizontal line 45, the vertex of which is at the point 36. In a curve representing a full 90° turn of the track, the acute angle 46 between the line 35 and the line 45 is equal to the angle 47 between the line 34 and the line 44. For any other curve, the angle 47 will vary in proportion, it being understood that the angle 46 is at the entrance of the curve and the angle 47 at the exit end. The length of the transition curve template 33 is a predetermined multiple of the distance between the line 41 and the line 45, which latter is constant for all standard radii. In the present instance, the length of the transition template 33 is one and one-half times the distance between the lines 41 and 45.

There is shown in Fig. 6 a group or series of sets of templates 32 and 33, arranged in the order of their progressively increasing radius and showing the proper relation therebetween when six or any other number of tracks are to be laid out parallel to one another. Also indicated therein is the establishing of the transition radius at three times the standard radius. According to this arrangement, it will be seen, radial lines tangent to those ends of the transition templates which abut ends of the standard radius templates pass through a common point which is also the point used as center for the standard radii. The distance between the points of tangency on all transition templates is equal.

In Fig. 7, a variation of the arrangement of Fig. 6 is shown in which the transition templates are omitted, the ends of the standard radius templates being in this instance brought into tangent or abutting relation to the end of the straight away portion of the track.

In Fig. 8 an arrangement is shown using templates 48 and 49 in like or combinations of different size to obtain a geometrically correct curve from one parallel track 51 to another 52.

In Figs. 10, 11 and 12 the manner of installing the templates is shown. Thus, in Fig. 10 a length of track is

stretched out to extend from the end of the straight away 42 from or through and beyond the line 41. The transition template is then placed with one end between the rails of the track, as indicated in Fig. 10 and the track then is bent until both rails lie outside respectively opposite edges of the template, whereupon the template is pressed into place between the rail as shown in Fig. 11. The standard radius template 32 then is similarly installed in the track beyond the transition template 33, with the adjacent ends of the templates being moved into substantially abutting and flush contact with one another. The desired radius or curvature, together with its easement or transition curve, thus is established and while the track continues to be held by the templates it is made fast to the road bed. The templates then are removed and to complete the curve the transition template 33 may be applied to the opposite end of the standard radius template, returning the track to a straight line 90° removed from the end of the straight away 42. In this regard, the ends of the templates provide a convenient and accurate guide for sawing off the track. Thus, by aligning the saw with the end of the template, a perfect tangential cut-off will be obtained and the rails will then match any other rails cut off parallel to any end of any template.

As seen in Figs. 6 and 9, the standard radius template 32 is inscribed with lines 53 indicating commonly used angles along the length of the template. In the use of these markings, the template is installed in the track and the track is marked as indicated in Fig. 13 at a selected angle. After spiking the track up to such mark, the template is removed and the track is sawed at the marked place. Then the transition template 32 is used, as indicated in Fig. 14, to bring the track from this cut-off point back to a tangent with another straight or another curved section.

In addition to previously mentioned advantages, the templates may be used in laying out wooden road bed, if it is desired to make one's own road bed rather than to use purchased material. A center line 50 of the curve is stamped on each end and makes this possible. Also, the dimensions of any template or set of templates may be used to establish a desired curve when making a preliminary layout on paper by ordinary drafting methods. After the preliminary layout is made and the curves established no further calculations or measurement is necessary on the actual layout. The templates will permit the track to fit in the exact location desired.

The three to one ratio that exists between the transition radius and standard radius, and the 1.5 to 1 ratio that exists between the distance from common center to the base line and the distance from radii tangency to the base line, permits ease of layout and absence of complicated calculation in the planning stages.

What is claimed is:

1. Rigid template means for forming curves in model railroad track, including a transition curve template and a full curve template, the first said template being made on a radius which is a predetermined multiple of the radius on which the second said template is made and said templates having approximately parallel ends adapted to abut one another.

2. Rigid template means for forming curves in model railroad track, including a curved plate made of a rigid material and adapted to interfit between the rails of a flexible track section, and another and similar plate made on a radius which is a predetermined multiple of the radius on which the first said template is made, one end of each of said templates being approximately parallel and adapted to abut one another and the other end of the second said template defining a line parallel to a line drawn through the focal point of lines radial with respect to the first said template.

3. Template means for forming curves in model railroad track, including an arcuate rigid plate adapted to

interfit between rails of a flexible track section to cause said track section to conform to the shape of said plate, said plate being made to correspond to and define a predetermined model railroading standard radius.

4. Template means for forming curves in model railroad track using a length of flexible track, including an arcuate rigid plate adapted to interfit between rails to cause the track to conform to the shape of said plate, said plate being made to correspond to and define a predetermined model railroad standard radius and having a width to be received between said rails with a press fit, at least one end of said plate having a radial formation.

5. Template means according to claim 4, characterized by another arcuate rigid plate adapted to interfit between rails in end to end relation to the first said curve to define a transition curve, said second plate having one end approximately parallel to said one end of the first said plate, said ends abutting in a line radial with respect to the first said plate.

6. Template means for forming curves in model railroad track using a length of flexible track, including a rigid arcuate plate formed on a radius standard in the model railroading art, the ends of said plate conforming to said radius, said plate having a width to be received between rails of said track, and another rigid arcuate plate adapted to be installed between the rails of the track in end to end relation to the first said plate to define in said track a transition curve leading into or out of the curve defined by the first said plate.

7. Template means according to claim 6, characterized in that the second said plate is formed on a radius which is a predetermined multiple of the radius on which the first said plate is formed, the adjacent ends of said plates substantially abutting one another in a line passing through the centers of the radii of said plates.

8. Template means for forming curves in model railroad tracks, including an arcuate rigid plate of a width to fit between the rails of the track, radial lines extending from any point along said plate passing through a common center, said plate being positioned to lie within a right angle having said common center as its vertex and to have one end thereof in predetermined constant angular relation to one side of said angle irrespective of the length and radius of said plate.

9. Template means for forming curves in model railroad tracks, including first and second arcuate rigid plates of a width to fit between the rails of the track, said plates being respectively formed to define a principal curve of standard radius and a transition curve, the latter having a radius which is a predetermined multiple of said standard radius, said plates being placed in substantially end to end relation to define said curves, said second plate having a length bearing a predetermined fixed relation to the distance between a line 90° tangent to the end of the straight away portion of the track and a parallel line passing through the center of said standard radius.

10. Template means according to claim 9, characterized in that the said distance between said parallel lines is constant for any one of a series of concentric standard radii whereby to make said second plate applicable for use with any one of a series of said first plates of progressively greater and lesser standard radius.

11. A method of laying curves in model railroad tracks, wherein the track comprises a flexible tie strip and flexible metal rails secured thereto, including the steps of forming a rigid template of a desired curvature and of a width snugly to interfit between the rails of the track, pressing said template into place on the track while bending the track to conform to the shape of the template, spiking the track to an under support while said template remains in place, and removing said template.

12. A method according to claim 11, characterized by the further steps of forming another template on a radius which is a multiple of the radius of the first said template, placing one end of said other template in adjacent substantially aligned relation to one end of the first said template, and conforming the track to said other plate to define in said track a transition curve leading into or out of the principal curve as defined by the first said template.

13. A method of laying model railroad track wherein the track comprises a flexible tie strip and flexible rails secured to said strip, including the steps of laying straight away track up to a predetermined point, installing in the track between said rails beyond said point a curved template, the track being bent to conform to the shape of said template, and similarly installing in the track between said point and the first said template a transition template of lesser curvature than the first said template, said transition template having a length greater than the distance between a line drawn through said point at right angles to the straight away and a parallel line drawn through the center of the radius of the first said template.

14. A method according to claim 13, characterized in that said distance is a constant for all radii of a standard series of radii from which the first said template may be selected, the length of said transition template being a predetermined fixed multiple of said constant.

15. A method of laying curves of 90° or less in model railroad track including the steps of placing in superposed relation to the track and in end to end relation to one another a curve template and a transition template, conforming the shape of the track to the curve defined by said templates, said curve template having a scale thereon, marking the track at a selected point along said scale, removing said templates and replacing said transition template in superposed relation to the track with one end thereof in adjacent aligned relation to the mark in said track, conforming the track beyond said mark to said transition template, removing said transition template, and spiking the track to an under support while said templates are in superposed relation thereto.
